UNITED STATES PATENT OFFICE.

SETH M. GOODER, OF CHICAGO, ILLINOIS.

BUILDING-MOVING EQUIPMENT.

Application filed February 5, 1925. Serial No. 6,944.

To all whom it may concern:

Be it known that I, SETH M. GOODER, a citizen of the United States, and a resident of Chicago, in the county of Cook and State 5 of Illinois, have invented certain new and useful Improvements in Building-Moving Equipments; and I do hereby declare that the following is a full, clear, and exact description thereof, reference being had to the 10 accompanying drawings, and to the characters of reference marked thereon, which form a part of this specification.

This invention relates to improvements in apparatus for moving heavy buildings, and 15 has been designed more especially for moving buildings, such as steel skeletons, brick, stone or concrete constructed buildings.

Among the objects of the invention is to provide a novel form of apparatus or equipment whereby the weight of the building is 20 supported on rails, suitably leveled and sustained, through the medium of caster elements, whereby the moving building is sustained through metal rollers and said rails, 25 thereby avoiding the use of numerous individual rollers to support the weight of the building through the known form of saddle plates and the consequent laborious handling and rehandling of said individual rollers.

Another object of the invention is to produce a building moving apparatus or equipment so constructed and arranged as to facilitate the movement of a building from 35 one street or roadway to an intersecting street or to a lot adjacent to a street without a multitude of individual rollers, as heretofore has been necessary, at turning points of moving buildings and without 40 driving into alignment a large number of rollers to progressive centers about which building is to be turned, the latter in accordance with well-known practice.

Another object of the invention is to produce a novel form of caster particularly 45 adapted for use in my improved apparatus or equipment, embracing a rugged frame carrying suitable rollers and suitable bearings therefor and connections to the shoe 50 timbers in such manner that the casters can swivel relatively to the shoe timbers.

A further object of the invention is to produce an improved and novel form of shoe 55 timber for use in building-moving equipments.

A further object of the invention is to produce a novel form of track rail on which the caster rollers rest and roll.

Other objects of the invention are to otherwise improve building moving apparatus, and the invention consists in the elements and combination of elements shown in the drawings and described in the specification, and is pointed out in the appended 60 claims.

In the drawings is shown a preferred embodiment of the invention, which is illustrated and described to disclose the principle involved in the present invention; but it will be understood that the details of construction may be considerably varied within the spirit and scope of the appended 65 claims, and that it is the intent to claim all of inherent novelty shown in the drawings and described in the specification.

In said drawings:

Figure 1 is a perspective view of a building sustained on a moving equipment embodying my invention.

Figure 2 is an enlarged fragmentary plan 80 view of one of the modified shoe timbers and one of the casters, partly broken away.

Figure 3 is a vertical section on the line 3—3 of Figure 2.

Figure 4 is a vertical section on the line 85 4—4 of Figure 3.

Figure 5 is a fragmentary perspective view of one of the supporting rails.

Figures 6 and 7 are perspective details 90 of parts of a caster member.

Figure 8 is a diagram illustrating the manner of laying the supporting track to direct a building from a street or roadway into another street or roadway at a right angle thereto, or into a lot at the side of a 95 roadway.

As shown in the drawings, 10, 10 designates, as a whole, shoe timbers by which the building is directly supported, as through the medium of the usual needles 11. Said 100 shoe timbers have heretofore been made of heavy timbers and carry saddle plates that engage the free rolling, individual rollers on which the building is supported and moves. As herein shown, the construction 105 is changed, in that the modified timbers are fabricated of metal shapes and permanently carry the casters or trucks by which the building is supported through rails, and whereby the building can be moved from 110

place to place. Said shoe timbers are usually placed beneath and parallel to, and at the sides of supporting walls, columns, or like upright structures of the building for the purpose of balancing the building structure to avoid twisting strains being set up that would tend to disrupt the structure. The length of the shoe timbers will depend upon the depth of the building from front to rear. They may, in practice, be of less length than the depth of the building and be suitably connected or scarfed at their ends to produce continuous shoe timbers. Said modified shoe timbers are shown as made of a pair of commercial channel shapes, arranged with their webs 22 vertical and parallel, and with their flanges disposed horizontally away from each other, thereby greatly strengthening the structure. Mounted on each shoe timber are a plurality of weight-transmitting and load-transporting caster elements, designated as a whole by 12, in Figure 1, and hereinafter described. Said casters are spaced at suitable distances along the length of the shoe timbers, and, by reason of the hollow construction of the modified shoe timbers, the casters can be embedded up in the space between the vertical members 22 thereof. The frames of the casters can also constitute means for attaching the members of the shoe timbers rigidly together. The casters include roller elements 14 which rest and roll on tracks, designated as a whole by 15.

These tracks are disposed parallel to and beneath the shoe timbers and are sustained and leveled on built-up longitudinally and transverse undertimbering 19 according to a common practice. Preferably, and in practice, the said tracks are of composite structure, being composed of channel shapes 16' and enclosed wood beams 17. The flanges of the channel shapes are vertical and their webs 18 are disposed horizontally to constitute upwardly facing tracks on which the rollers 14 of the casters 12 are supported. Preferably and as herein shown, each track has a wide supporting face and is divided by a central, longitudinally extending rib or strap 20, to sustain twin roller casters, wherein the rollers are disposed end to end, as will hereinafter more fully appear. The presence of this strap or rib upon the face of the track constitutes a control to prevent the caster rollers from slipping sidewise off the track. Said control ribs are preferably made separate from and detachably fixed to the channels, so that they can be used or not, as desired.

The rollers of each caster are mounted in endwise, coaxial relation to rotate on a massive axle or shaft 25, the trunnion ends 26 of which enter downwardly opening sockets

27 in diametrically thickened portions of a horizontal body ring 28, whose outer diameter substantially fills the space between the webs of the shoe timber channels. The rollers 14 are of composite structure, as best shown in Figure 3. Each comprises a peripheral, broad-faced steel or other hard metal ring 30 to produce a tread to rest on the appropriate half of the track 15, and an inner reinforcing and bearing collar 31 which is fast in said ring. 32 designates a hard metal bearing collar on the axle 25. Between said collars 31 and 32 are disposed spherical or other bearings 33 to transmit the load through an anti-friction medium. When the track-dividing or control rib 20 is employed and twin rollers are employed in the caster, the shaft 25 can be centrally supported and reinforced by a bar or diaphragm 35 which extends diametrically across the ring 28 and is set at its smaller ends 35' into downwardly opening recesses of the caster structure ring 28. Said reinforcing bars when used are of considerable depth at their longitudinal centers, and are perforated to fit closely on an intermediate part of the axle 25. This arrangement greatly strengthens the caster structure and also reinforces the axle against deflection. If desired, the tread rings of the rollers are closed at their outer ends by plates 14' to prevent entrance, through the outer ends of said rings, of dust and dirt to the roller bearings.

The ring 28 constitutes the lower element of a turntable whose turning axis lies between the webs 22 of the shoe timber. 36 designates an upper ring member of said turntable, and 37 designates the horizontal web of a channel plate or ring 38 which extends between the webs of the modified shoe timber channels and can be rigidly fastened thereto by the screws or bolts 39 and 40 and the angles 41 which lie in the angles between the plate 37 and the webs 22 of the shoe timber beams. The angles 41 and said channels 38 bear against the webs of the shoe timber beams and thus, not only strengthen the caster structure, but also reinforce the connection between said structure and said beams and the structure of the shoe timbers.

An annular series of anti-friction bearings 43 are interposed between the upper ring 36 and the lower ring 28, and are held in place by a familiar form of cage 44. The central opening in the web or plate 37 affords clearance for the projection of the caster rollers, as shown in Figure 3. A vertically disposed shell 46, is closely fitting within the hollow caster elements 28, 36, and 37 to hold the antifriction cage in place.

From what has been said, it will be evident that the caster or turntable structure, connected as it is to the elements of the

modified shoe timber, constitutes a connecting and reinforcing bridge element between said channel shapes; and it is also evident that the rollers 14 are capable of rotating about the axis of rotation of the turntable between the shoe timber beams so as to adapt the casters to travel on curved tracks as well as straight tracks, as clearly indicated in Figure 8. Figure 8 indicates the simplicity of laying a curved connecting track between straight or tangent tracks, with the curved portion of the track developed about a single center point. In the straight parts of the track approaching to and receding from the curved portion of the track, the control ribs 20 are removed, as well also on the curved portions of said track. Each shoe timber is shown in Figure 8 as equipped with seven casters and the curved track rails can be so laid that three rails will support the caster roller elements of three pairs of roller elements while the fourth rail can support the roller elements of the center caster of a shoe timber. Thus by properly cutting or aligning the roller elements to a single center, the work of turning a corner can be done as a simple job with the aid of a few operatives. The rails will be supported by the necessary matting or under timbering, which will only need to be limited to the width of the active portions of the track, whereas in prior practice it has been necessary, by the use of a multitude of individual rollers, to mat the surface from side to side of the street or roadway at the turning point. It is also evident that the friction developed between the axle and rollers under load stress and that developed between the elements of the turntable is minimized by the annular series of anti-friction bearings 35 and 43. Therefore, the casters are free to turn on their axle 25 and also about a vertical axis to permit swiveling movement of the caster rollers in their frames.

Reference herein made to the term "shoe timber" and "shoe timbers" is not intended to exclude the particular material of which such element or elements are made. Inasmuch as the term shoe timber has acquired a definite status in the old art, this term has been here used notwithstanding the fact that in the preferred form of the invention, though not exclusively, such element or elements are made of metal.

I claim as my invention:

1. A building moving equipment including a composite supporting track comprising a channel plate and a wood filler between and extending below the flanges of the plate, the web of said channel constituting the track face and being provided with a central caster control rib.

2. In a building moving equipment, the combination with a shoe timber and cylind-

ric metal roller casters fixed to said timber, of a metallic track on which the rollers of said casters rest and roll.

3. In a building moving equipment, a shoe timber and a caster fixed thereto embracing a cylindric supporting roller, combined with a flat metal supporting track for said roller.

4. In a building moving equipment, a hollow shoe timber and a plurality of roller casters swiveled to said timber and spaced along the length thereof and partially enclosed therein.

5. In a building moving equipment, a downwardly opening shoe timber and a plurality of caster frames enclosed in said timber and spaced along the length thereof, and rollers swiveled in said frames.

6. A building moving equipment including a shoe timber comprising fabricated metal beams, and roller casters between and fixed to said beams and constituting elements to fasten said beams to each other.

7. A building moving equipment including a shoe timber comprising spaced beams having vertical members, and roller casters having frames disposed between and rigidly attached to said vertical members of the beams.

8. A building moving equipment including a shoe timber comprising spaced beams, and a roller caster comprising a frame rigidly fixed to vertical elements of said beams, and including a turntable, and rollers mounted in said turntable.

9. A building moving equipment including a shoe timber comprising spaced, metallic channel beams with their flanges directed outwardly, and a roller caster comprising a frame, means to fixedly attach the frame to the webs of the beams and to connect said beams together, and caster rollers rotatively mounted in said frame.

10. A building moving equipment including a shoe timber comprising spaced, metallic channel beams with their flanges directed outwardly, and a roller caster comprising a frame, means to fixedly attach the frame to the webs of the beams and to connect said beams together, said frame including a turntable, a shaft rotatively mounted in the turning part of said table, a roller mounted on said shaft, and antifriction bearings between said roller and shaft.

11. A building moving equipment comprising a horizontal shoe timber and a cast-er frame fixed thereto, said frame including a turntable rotatable on a vertical axis, a shaft in said frame and a cylindric caster roller mounted to turn on said shaft.

12. A building moving equipment comprising a shoe timber including spaced, metallic beams, a plural roller caster including a frame fixed to said beams and rigidly connecting them together as a unitary structure, a massive shaft supported in said frame, and

1 a plurality of rollers arranged end to end, and rotative, on said shaft.

13. A building moving equipment comprising a shoe timber composed of spaced metallic beams, a plural roller caster including a frame fixed to said beams and connecting them together to constitute a unitary structure, said caster frame including a turntable, a massive shaft supported in said turntable, and a plurality of rollers arranged end to end and rotative on said shaft.

14. A building moving equipment comprising a hollow shoe timber, a roller caster frame inserted in the hollow shoe timber and fixed thereto, and supporting rollers mounted thereon and projecting below the level of said shoe timber.

15. A building moving equipment comprising a shoe timber including spaced metallic beams and a roller caster therebetween including a rigid frame connected to said beams and constituting a connecting bridge between said beams, said frame including means whereby the axis of rotation of said 25 caster can turn on a vertical axis parallel to said beams.

16. The combination with a shoe timber comprising spaced parts, of a dual roller caster between said parts comprising an upper ring member between and fast to said parts and a lower turntable member, an axle mounted in said turntable member, spaced rollers rotatable on said axle, and a brace member supported on said turntable member and extending between said rollers and having an open portion to receive and afford bearing for and to support said axle between said rollers.

17. In a building moving equipment, a two part shoe timber, and a caster between said parts comprising an upper ring rigidly fixed to said shoe timber parts, an axle, a caster roller rotatively mounted thereon, antifriction bearings between said axle and said roller, a turntable part to support said axle and antifriction bearings between said ring and said turntable.

In witness whereof I claim the foregoing as my invention, I hereunto append my signature this 26th day of January, 1925.

SETH M. GOODER.
